UNITED STATES PATENT OFFICE.

CARL W. A. KOELKEBECK, OF PITTSBURGH, PENNSYLVANIA.

METHOD OF AND APPARATUS FOR THE MANUFACTURE OF STRUCTURAL SHAPES.

Application filed July 9, 1925. Serial No. 42,414.

This invention relates to the manufacture of structural shapes such for instance, as I-beams, channels and the like.

According to the present invention, it is proposed to associate with a mill for the production of rolled structural shapes, means for removing a portion of the web of the beam or other structural shape for the purpose hereinafter set forth.

With the present invention, such removal of a portion of the web is effected in the ordinary practice of rolling with only some slight addition to the equipment now generally provided.

The resulting product is a structural element having practically all of the strength of a shape having a solid web, but having considerably less metal and weight than a solid web beam of the same dimensions, and considerably more strength than a beam of corresponding weight. This product is the subject of a copending application, Serial No. 47,261, filed July 31, 1925.

This invention may be best understood by reference to the accompanying drawings which illustrate in a more or less diagrammatic fashion, a preferred embodiment of the principles of my invention, but to the specific construction of which the invention is not restricted. In the drawings:

Fig. 1 represents a plan view of rolling mill with my invention applied thereto.

Fig. 2 is a view similar to Fig. 1 of a slightly modified arrangement.

Fig. 3 represents a longitudinal section through a form of punch arranged for use with the present invention.

Fig. 4 is a transverse view of the press shown in Fig. 3.

Figs. 5 and 6 are views corresponding to Figs. 3 and 4, respectively, of a different form of punch.

Fig. 7 is a side elevation of a section of the finished product.

Fig. 8 is a transverse section in the plane of line VIII—VIII of Fig. 7.

Referring first to Figs. 7 and 8, 5 designates a portion of the length of an ordinary structural shape, such as an I-beam, with a central web 6 and upper and lower flanges 7.

The neutral axis of the beam, which in the particular form shown, is its central axis, is designated by the line a—a. Punched in the web are holes 8. While I have shown these holes as being symmetrical about the neutral axis, the principle of the invention

is not so restricted. Removal of the metal to form the several holes 8, the total area of which represents a considerable percentage of the total area of the web, effects a considerable reduction in the overall weight of the beam as well as a material saving of metal. Thus it enables the height of the structural web to be materially increased without proportionately increasing its average weight per foot. An increase in the height of the web materially increases the moment of resistance of the structure. Thus, the practical effect of removing the metal along the neutral axis of the structural beam is to materially increase the strength of a beam with respect to its weight. This is according to the formula:

$$R = \frac{bh^2}{6} \quad 75$$

in which R is the moment of resistance, b the width, and h the height of the beam, while 6 is a constant. Assume this formula as applying first to a bar six inches high and two inches wide.

Then,

$$R = \frac{2 \times 6^2}{6} = 12. \quad 85$$

Assume next, a bar two inches wide and twelve inches high with six inches of the web removed equally about its neutral axis, as shown in Figs. 7 and 8, so that there remains only the area of metal found in a bar six inches high plus the practically negligible area of the metal between the holes. 90

Then,

$$R = \frac{2 \times 12^2 - 2 \times 6^2}{6} = \frac{2 \times 144 - 2 \times 36}{6} \quad 95$$

$$R = \frac{288 - 72}{6} = \frac{216}{6}$$

$$R = 36. \quad 100$$

Thus, in the example given, it may be seen that by increasing the weight of a beam only to the amount required for the connecting portions between succeeding openings, the moment of resistance of the beam may be trebled.

The present invention relates more particularly to a means and method for commercially producing a structural element as described in connection with Figs. 7 and 8. 110

In Fig. 1 of the drawings, A designates a roughing mill of any standard or preferred

form and B designates a finishing mill. Suitable transfer tables C may be provided in connection with this mill, for manipulating the beam as desired. The tables may be of any suitable construction, but are preferably of the type diagrammatically indicated, having power driven rollers therein. At D, is a run-out table as generally provided and E represents a hot bed of a type commonly employed, adapted to receive the rolled product and from which the rolled product may be transferred to a second roller table or conveyor F.

So much of the equipment as has been described is usually employed in structural mills of the present type.

According to the preferred form of the present invention, it is proposed to provide a second run-out trough or table G, parallel with D, so that the product of the finishing mill B may be fed onto table G by shifting a transfer table C into alignment therewith, instead of onto table D.

Reciprocable transversely across the table G at a suitable point is a cropping saw of any standard or preferred construction and diagrammatically shown and designated H. Disposed rearwardly of this, is a pair of power driven feed or pinch rolls I. At J is indicated a punch of the vertically reciprocating type and K designates a rotary punch. Two punches are preferably provided in the installation, the former for large structural units and the latter for operation on smaller stuff.

The punch J is of more or less standard construction, and is shown in detail in Fig. 3. It includes a die or base member 10 disposed under the run-out table G rearwardly of the feed rolls I, and the top of the die is flush with the tops of the rollers so that the beam 5 will be supported thereon during the punching operation. Spanning the table G above the die is a supporting arch 11 which carries a pressure cylinder 12 for effecting reciprocation of a punch 13. Obviously, any suitable power press may be substituted.

The punch K, for operation on smaller work, is preferably of a rotary type, shown somewhat in detail in Figs. 5 and 6. In these drawings, 14 designates a lower roll transverse to the table G and having its edge arranged to be just below the beam 5 as it rolls along thereover. In this cylinder is an opening 15 around which is a portion of the roll to provide a support and cutting edge against which the beam 5 bears during the pressing operation.

Above the table G directly over the lower transverse roll is a second transverse roll 16, having a punch or perforator 17 on its periphery. These rolls are driven in synchronism so as to bring die 15 and punch 17 opposite each other at the same time, at which time a part of the web of beam 5 is punched out, as shown

in Fig. 5. Thus holes may be punched in the web of the beam at regular intervals and in a continuous manner.

In the table G, rearwardly of the said second punch, is a pair or stand of finishing rolls L, preferably of the universal type which function to flatten out and smooth over any distortion resulting from the punching process. The end portion of table G may run along a second hot bed, designated 18.

In carrying out the invention, the shapes are first rolled in the usual manner, first in the roughing rolls and then in the finishing rolls B, and then while they are still hot, they are punched and smoothed out. The pinching rolls I serve to feed the shapes forward as they are punched.

However, it may happen, that after the beams are punched, they will have cooled to a point where it is desirable to reheat them before they are smoothed out. If reheating is desired, a furnace N may be provided in the table G beyond the punches, as shown in Fig. 2, which is otherwise similar to Fig. 1. Fig. 2 also suggests the use of a suitable straightening device, as at O for straightening the punched product, mechanism O to be used in addition to rolls L.

While I have described a preferred arrangement of the apparatus, and shown it in connection with present standard rolling mill equipment, it will be understood that the arrangement and organization may be varied within the spirit of the invention and under the scope of the appended claims.

I claim as my invention:

1. A mill for the manufacture of structural shapes, including rolling units, a run-out table arranged to receive the finished product of said units while the same is hot, a punch associated with the run-out table for removing a part of the central portion of the shapes, and finishing rolls along the run-out table beyond the punch.

2. A mill for the manufacture of structural shapes, a run-out table associated therewith, a punch to which the run-out table delivers, and finishing rolls beyond the punch.

3. A mill for the production of structural shapes, including rolling units, a run-out table associated therewith, a transfer table for receiving a shape from the rolling units and delivering it onto the run-out table, a punch over the run-out table, a reheating furnace beyond the punch, and finishing means beyond the reheating furnace.

4. A mill for the production of structural shapes, including rolling units in which finished shapes are formed, a transfer table for receiving a finished shape therefrom, a juxtaposed run-out table to which the transfer table delivers, a cropping saw associated with the run-out table, a punch associated with the run-out table beyond the saw, and finishing rolls beyond the punch.

5. A method of forming open web structural beams which consists in passing newly rolled shapes directly from a mill to a perforator and perforating the webs thereof before the shapes are cold, and then passing the shapes through finishing rolls to remove irregularities produced in punching.
6. A method of forming open web structural shapes which consists in passing the completed shapes from a rolling mill directly to a punching means and punching the same before they are cold, then heating the punched shapes, and passing them through finishing rollers.
10. 7. A method of forming open web structural shapes which includes forming the shapes by a hot rolling process in a mill, delivering the shapes from the mill to a run-out table, trimming the ends of the shapes as they move

along the table, punching holes in the webs 20 of the shapes as they move along the run-out table, and finally finishing the punched shapes in a suitable finishing roll.

8. A mill for the manufacture of structural shapes, a run-out table associated therewith, means for delivering the shapes to the run-out table, a perforator to which the run-out table delivers, and a finishing stand beyond the perforator comprising a universal mill.

30 9. A mill for the manufacture of structural shapes, a run-out table associated therewith, a perforator to which the run-out table delivers, a reheating furnace beyond the perforator, and a finishing stand comprising a universal mill beyond the furnace.

In testimony whereof I affix my signature.
CARL W. A. KOELKEBECK.
